UNITED STATES PATENT OFFICE

WILLIAM STRICKER, OF KANSAS CITY, MISSOURI

NEEDLE

Application filed April 28, 1928. Serial No. 273,549.

My invention relates to improvements in latch needles such as are employed in repairing knitted goods of a fine quality of silk, cotton thread, etc. With knitted goods of 5 the foregoing character it often happens that the thread breaks and causes a run or ravel in the fabric.

The method employed in mending the article consists in looping each portion of the 10 thread forming the run with the succeeding portion and securing the last loop formed at the end of the run with a piece of thread corresponding to the threads from which the article is manufactured.

15 With the latch needles usually employed in mending the fabric the latch of the needle must be forced open by pressing against the thread. This method of opening the latch is slow, tedious, and trying both to the eyes and 20 patience of the operator as each separate thread must be picked up by the hook at the forward end of the needle and if the latch is not open when the needle is advanced said latch will become entangled in the fabric 25 and possibly result in dropping the stitch or breaking the thread.

My invention overcomes the foregoing objection by providing mechanical means for automatically and positively opening the 30 latch at the proper time. This speeds up the work to such an extent that the threads can be picked up faster than the eye can see and therefore relieves the eyes of strain.

In addition to being used manually my 35 needle can be readily adapted for use on automatic knitting machinery with which more or less difficulty is now experienced by the old type of needle dropping stitches and breaking threads, thereby forming runs 40 which must be repaired manually when the work is taken from the machine. The foregoing difficulty can be eliminated by the use of my needle as the latch thereon is automatically and positively thrown open at the 45 proper time and hence cannot become entangled with and break threads or cause the needle to drop stitches.

In order that the invention may be fully understood reference will now be had to the 50 accompanying drawing, in which:

Fig. 1 is an enlarged broken side elevation of the needle with the latch open.

Fig. 2 shows the latch closed against the tension of the spring means whereby it is automatically opened. 55

Fig. 3 is an enlarged detail side elevation of the spring means for automatically opening the latch.

Figs. 4, 5 and 6 show a series of diagrammatic views of the method of repairing a run with a manually operated needle embodying 60 my invention.

Fig. 7 shows a modified form of needle adapted for use in a knitting machine.

Referring in detail to the different parts, 65 2 designates the needle arranged for manual use and consisting of a staff 4, a handle 6 formed at the rear end of said staff 4, a hook 8 formed at the forward end of the staff 4, a latch 10, and a long spring 12 for throwing the latch to open position. The hook 8 tapers toward its front end 13, so that it can be more readily inserted between the closely arranged threads of the fabric than is possible with the blunt needle in general use. 70

The side 14 of the staff has a longitudinal recess 16 for the reception of the spring 12 so that the surface 17 of the latter will be flush with the surface of said side 14 and thereby enable the spring 12 to pass through 75 a loop with the needle without catching upon the thread.

The latch 10 is mounted at one end upon a pivot 18 which extends through the opposite sides of the slotted portion 20 of the needle. 80 The spring 12, which is formed from a suitable length of spring metal, is spot-welded or otherwise fixedly secured near its rear terminal 22 to the staff 4, while its forward end 24 is curved to enter the slot 20 and engage the latch 10 at a point in advance of the pivot 18 for the purpose of automatically throwing 85 said latch to open position.

In practice, when mending a run in a silk stocking or other knitted article, the part to be mended is stretched over the fingers, a cup, a glass or other suitable support. The operator first inserts the hook 8 through the loop *a* at one end of the ravel and then advances the needle until said loop *a* slips over 90 95 100

the free end of the open latch 10 and the hook is engaged with the succeeding thread *b*, as shown by Fig. 4. The needle is then pulled backwardly and carries the open latch 10 against the loop *a* which closes said latch against the tension of the spring 12, as shown by Fig. 5. The latch 10 is held in closed position by the loop *a* until it passes out of engagement with said loop *a* after which said latch is instantly thrown to the open position disclosed by Fig. 6, by the spring 12 and is ready for the next forward movement of the needle, thereby making more rapid progress possible than with the old type of needle as there is no danger of the open latch 10 catching in the threads or fabric on the forward stroke. The foregoing operations are repeated until the run is repaired, whereupon the end is secured by a thread or stitch in the usual manner to prevent the entire repair from raveling out.

From the foregoing description it is apparent that I have provided a needle embodying the advantages above pointed out, and while I have shown a preferred form of said needle I reserve all rights to such changes and modifications thereof as properly fall within the spirit and scope of the invention as claimed.

Having thus described my invention, what I claim and desire to secure by Letters Patent, is:

A needle consisting of a staff having a slot in its forward portion and a longitudinal recess in one side and extending backwardly from the rear end of the slot, a hook at the forward end of said staff, a latch having one end pivotally mounted within the slot, and a long spring arranged in the longitudinal recess and bent at its forward end to project into the slot and engage said latch a short distance in advance of its pivotal point.

In testimony whereof I affix my signature.
WILLIAM STRICKER.
